Patented Aug. 26, 1919.

INVENTOR:
James Stuart Wear
Wm Wallace White, ATTY.

UNITED STATES PATENT OFFICE.

JAMES STUART WEARN, OF LINWOOD, CHRISTCHURCH, NEW ZEALAND.

INDOOR GAME OF SKILL.

1,314,293.

Specification of Letters Patent. Patented Aug. 26, 1919.

Application filed April 20, 1918. Serial No. 229,669.

To all whom it may concern:

Be it known that I, JAMES STUART WEARN, a subject of the King of Great Britain, residing at 11 Cuba street, Linwood, Christchurch, in the Dominion of New Zealand, have invented certain new and useful Improvements in Indoor Games of Skill, of which the following is a specification.

This invention relates to an indoor game of skill, its object being to provide a game that may not only be played by any person, but which will also be scientific and provide ample scope for skill.

In order that the nature of the invention may be fully understood, reference will now be made to the accompanying sheet of drawings in which:

Figure 1—is a plan view of the apparatus showing the arrangement of the various parts and in which by way of illustration are indicated in dotted lines, certain possible strokes in the game, and

Fig. 2—is a cross-section through the line A—B Fig. 1.

The apparatus comprises a board or table-top 1 of convenient size which is preferably covered with baize or similar material. Near one end of the table 1 is secured a pair of pins or studs 2 to each of which is attached a circular rubber or other resilient disk 3 adapted to provide a circular cushion surface or round buffer for the ball which is used in the game to strike against. In construction, each of the studs 2 may be conveniently formed at a height approximating to the center of the ball, with a circumferential groove 4 adapted to receive the rubber 3 in annular pad or ring form so as to be capable of being sprung into place, as clearly illustrated in Fig. 2. These circular cushions, as they will be termed 3, are disposed in line with one another at right angles to the length of the table at suitable distances apart, while arranged in circular form or fan-wise around the table at a common radius from a center mid-way between the said circular cushions, and at equal intervals apart are a number of small pegs or studs 5, securely fixed to the surface of the table 1.

These studs which are preferably provided with resilient cushions 6 similar to the cushions 3, are arranged to extend in the manner already explained around approximately three quarters of a circle so as to provide an interval or clear space on the table immedi-

ately in front of the circular cushions 3 and so provide a free passage for the ball.

Between each two of the pegs 5 and in line therewith is placed a pin 8 similar to those employed in skittles, but somewhat smaller, 60 each pin being numbered according to its position in relation to the cushions 3.

The game itself consists in placing a ball 7, which is preferably a bagatelle or billiard ball, at the far end of the table 1 and, by 65 means of a cue, to direct such ball against one of the circular cushions 3 and strike it at such an angle that it will rebound or carom on to any of the pins 8, so knocking the latter down. The ball may also be directed so as to carom off one of the fixed pegs 5 and from thence to perform a second carom off one or other of the circular cushions 3 to the particular pin 8 the player desires to knock down. Various strokes of 70 this kind are indicated by dotted lines in Fig. 1 and from which it will be seen that the game affords great scope for the exercise of skill and judgment on the part of the players.

It will be understood that, if only one cushion 3 were employed and that placed in true central relation to the pins 6 it would be practically impossible to cause the ball to carom off such cushion 3 on to a pin immediately in rear of it. By having two cushions, however, placed a short distance apart it would be possible to carom off either one or other of such cushions on to any pin on the board, the more difficult ones to knock over 75 being given a higher scoring value than the easier ones.

Should it be so desired, however, but a single cushion may be employed as the more obscure points on the board may be reached 80 by causing the ball to perform a second carom off one or other of the pegs 5.

To prevent the ball from rolling off the table surface, an upwardly extending flange 9 may be arranged to extend around the edge 100 of such table and such flange may be positioned at a sufficient distance from the pegs 5 and pins 8 as to permit a free run for the ball which upon reaching the flange will simply follow the latter until coming to rest. 105 If desired, in cases where a special table is employed, suitable openings or traps may be provided in this dead space so as to allow the ball to fall therethrough on to an inclined chute by means of which it will be returned 110

to the player in a manner similar to that employed in skittles. Suitable rules may be devised to adapt the game for use of a person of any age.

5 I claim:—

1. In combination, a game board, fixed studs upstanding from said board, an arcuate series of fixed pins partially surrounding said studs, and movable pins between said

10 pins.

2. In combination, a game board, an arcuate series of fixed pegs upstanding from said board, fixed studs arranged eccentrically of said pegs, and movable pins between said

15 pegs.

3. In combination, a game board, a series of fixed pegs and movable pins arranged

alternately in the form of a split annulus, and fixed studs within said series of pins and pegs.

20

4. In combination, a game board, an arcuate series of fixed pegs upstanding from said board, fixed studs arranged eccentrically of said pegs, movable pins between said pegs, said studs and pegs being formed with annular grooves, and cushioning members mounted in said grooves.

25

In witness whereof I have hereunto set my hand in the presence of two witnesses.

JAMES STUART WEARN.

Witnesses:

CYRIL CARLYN CORBET,
PAIDNEY JAMES TRELEAVES.
